^{Inventor}
Hugo W. Miller.

By *Grace C. Miller*
^{Attorney}

UNITED STATES PATENT OFFICE.

HUGO W. MILLER, OF NOGALES, ARIZONA.

DECIMAL DIE.

Application filed September 27, 1923. Serial No. 665,130.

To all whom it may concern:

Be it known that I, Hugo W. MILLER, a citizen of the United States, residing at Nogales, in the county of Santa Cruz, State of Arizona, have invented certain new and useful Improvements in Decimal Dice; and I do hereby declare the following to be a full, clear, and exact description of the invention, such as will enable others skilled in the art to which it appertains to make and use the same.

This invention relates to new and useful improvements in games, and particularly to game pieces therefor.

The principal object of the invention is to provide a game piece, which is in the form of a die, same being arranged to be spun on either of its ends, instead of being rolled, as with the ordinary cubic die.

Another object is to provide a game piece of this character which has numbers thereon from 0 to 9, thus producing a decimal die, instead of the usual die which is number from 1 to 6.

Other objects and advantages will be apparent from the following description when taken in connection with the accompanying drawing.

In the drawing:

Figure 1 is a side elevation of a die made in accordance with the present invention.

Figure 2 is an end elevation of the same.

Referring particularly to the accompanying drawing, 10 represents the body of the die, which is spherical in general outline, but formed, around the intermediate portion of the body, in the form of a belt, are the series of flat faces 11, said faces being differently colored and each having a number thereon. There are ten faces, number from 0 to 9, these faces may also be considered as five pairs of faces, each face of a pair being in a plane parallel and diametrically opposite to the other. The arrange-

ment of the numbers on these pairs of faces is optional, although such an arrangement whereby to make the sum of the numbers on the faces of each opposite pair total nine, would be advantageous.

It will, of course, be understood that the colors shown and described, are merely illustrative and such colors may be changed as desired. However, it is desirable to have the faces number 6 and 9 of different colors so that they may readily be distinguished from each other. As a further point of distinguishing the 6 and 9, the common manner of placing a horizontal line beneath each number to show the bottom thereof, may be adopted, as shown in Figure 1.

The game piece is arranged to be placed on one or the other of its rounded ends 12, and spun thereon. When the piece ceases to spin, it will come to rest on one of the flat faces, the uppermost face being the one to be observed in scoring points in the game.

Obviously the use of the colors in conjunction with the numbers serves a double purpose, one in connection with the scoring of points in the numerous games adaptable to the piece and the other in making it attractive to the eye, hence the selection of a definite color scheme is left optional.

What is claimed is:

A game piece having a body in the general form of a sphere formed with a circular series of flat faces arranged in diametrically opposite pairs, around the intermediate portion thereof, the opposite end portions of the body being smooth and unobstructed for rolling contact with a surface.

In testimony whereof, I affix my signature in the presence of two witnesses.

HUGO W. MILLER.
